[57] CLAIM

The ornamental design for a golf club head, as shown and described.

DESCRIPTION

FIG. 1 is a front elevational view of a golf club head showing my new design;

FIG. 2 is a right side elevation thereof, which is the mirror image of the left side;

FIG. 3 is a top view thereof on line 3—3 of FIG. 1;
FIG. 4 is a bottom view thereof on line 4—4 of FIG. 1;
FIG. 5 is a rear view thereof on line 5—5 of FIG. 2;
FIG. 6 is a cross-sectional view thereof on line 6—6 of FIG. 3, it being understood that the oval shaped line on the left side of FIG. 3 is identical to the one on the right side; and

FIG. 7 is a cross-sectional view of another embodiment of the invention which is identical to that of FIGS. 1—6 except that the E-shaped design and the oval shaped lines on the top of the club head are raised instead of recessed, the view of FIG. 7 being taken at the comparable location as line 6—6.
